UNITED STATES PATENT OFFICE.

WILLIAM H. ELY, OF MIDDLETOWN, CONNECTICUT.

DESIGN FOR AN EYEGLASS-BRIDGE.

SPECIFICATION forming part of Design No. 34,751, dated July 9, 1901.

Application filed April 17, 1901. Serial No. 56,323. Term of patent 14 years.

To all whom it may concern:

Be it known that I, WILLIAM H. ELY, a citizen of the United States, residing at Middletown, in the county of Middlesex and State of Connecticut, have invented and produced a new and original Design for an Eyeglass-Bridge, of which the following is a specification.

The accompanying drawing, which forms a part of the specification, shows a perspective view of an eyeglass-bridge having my design.

As shown in the view, the leading or material feature of the design is the flat arch, with loops on the upper side of the ends of the arch rising to substantially the plane of the top of the arch and ends that extend downwardly from the inner sides of the loops.

The bridge curves downwardly toward each side, forming the arch 1, and then curves upwardly, inwardly, and again downwardly, forming the loops 2 and leaving the attaching ends 3 extending downwardly from the inner sides of the loops.

Having described my invention, what I claim as new, and desire to secure by Letters Patent, is—

The design for an eyeglass-bridge herein shown and described.

WILLIAM H. ELY.
